United States Patent Office

Des. 206,560
Patented Dec. 27, 1966

206,560

SEWING MACHINE OR SIMILAR ARTICLE

Sidney J. Hamlett, Parma, Ohio, assignor to White Consolidated Industries, Inc., Cleveland, Ohio, a corporation of Delaware

Filed Mar. 2, 1966, Ser. No. 1,255

Term of patent 14 years

(Cl. D70—1)

Fig. 3

FIG. 1 is a perspective view of the front and right sides of a sewing machine showing my new design;

FIG. 2 is a perspective view of the right and rear sides of the sewing machine; and

FIG. 3 is a perspective view of the left and rear sides of the sewing machine.

I claim:

The ornamental design for a sewing machine of similar article, as shown.
